OTHER PUBLICATIONS

(74) **Attorney, Agent, or Firm** — Banner & Witcoff, Ltd.(57) **CLAIM**

The ornamental design for an input device for an electronic tablet, as shown and described.

DESCRIPTION

FIG. 1 is a top isometric view of an input device for an electronic tablet showing the new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken line showing of various features on the input device for an electronic tablet in the figures are for environmental purposes only and form no part of the claimed design.
